UNITED STATES PATENT OFFICE.

HENRY F. MARTEN, HENRY GRAHN, AND JULIUS C. ANDRESEN, OF SAN FRANCISCO,
CALIFORNIA.

BARREL-STAVE-NUMBERING APPARATUS.

1,266,840.

Specification of Letters Patent. Patented May 21, 1918.

Application filed November 20, 1917. Serial No. 202,917.

To all whom it may concern:

Be it known that we, HENRY F. MARTEN, HENRY GRAHN, and JULIUS ANDRESEN, citizens of the United States, residing at the city and county of San Francisco and State of California, have invented certain new and useful Improvements in Barrel-Stave-Numbering Apparatus, of which the following is a specification.

10 Barrels and other cylindrical containers of the stave type are formed at a cooperage plant and then in a knocked down condition, in order to save transportation space, are shipped to the point to be used and then 15 re-assembled. When the staves of the barrel or receptacle are temporarily assembled and are temporarily held together by the temporary hoops it is necessary to mark the staves or indicate the same in such manner 20 so that the staves after the barrel or receptacle has been knocked down and it is desired to re-assemble the same, may be positioned properly relative to each other. The present practice in so marking the staves of a 25 barrel or other cylindrical container is to employ a stencil for positioning over the temporarily assembled barrel and to use in connection therewith a suitable brush for forcing the ink through the openings of the 30 stencil onto the staves, one mark or a portion thereof being made on each stave in some consecutive order so that it will be possible to properly assemble the staves with the staves consecutively arranged after 35 the barrel has been marked out. This is a costly and slow proposition, and the capacity of one operator in performing this operation is very limited thereby in a cooperage plant of any great output several 40 markers or stencilers are required.

The present invention has to provide a construction wherein this operation of marking staves of a barrel when temporarily assembled together is accomplished 45 while the barrel is being rotated and worked in a crozing, chamfering or hollowing machine or in fact any type of machine for operating on a temporarily assembled barrel wherein the barrel is rotated while the same 50 is being operated upon, thereby dispensing with the marking operators and marking the barrel while some other required work on the same is being performed, thereby re-

ducing the cost of marking a barrel to a minimum and insuring that the staves of each barrel will be properly marked as the function of marking the same is performed during some necessary operation on the barrel.

The invention consists broadly in a marking member provided with suitable marking characters supplied with a marking medium by a suitable member in contact therewith, the marking member being held in contact with the staves of the barrel during the rotation thereof so that indications on the exterior of the staves circumferentially of the barrel will be made on one complete rotation of the barrel in its operation. The marking member is preferably moved a slight distance longitudinally of the barrel to prevent the overlapping of the opposite ends of the marking on the barrel.

With the above mentioned and other objects in view, the invention consists in the novel construction and combination of parts hereinafter described, illustrated in the accompanying drawings, and set forth in the claims hereto appended; it being understood that various changes in the form, proportion, size and minor details of construction within the scope of the claims may be resorted to without departing from the spirit or sacrificing any of the advantages of the invention.

To more fully comprehend the invention reference is directed to the accompanying drawings, wherein,

Figure 1 is a view in side elevation of a suitable barrel operating machine or apparatus, with the preferred embodiment of our invention applied thereto.

Fig. 2 is a vertical sectional view of the barrel operating mechanism illustrating the printing and marking rollers and the manner of mounting the same.

Fig. 3 is a view in detail of the printing or marking member; and

Fig. 4, is a view in detail of the mechanism for causing longitudinal movement of the printing or marking member relative to the barrel on each revolution of the same.

Referring more particularly to the accompanying drawings, wherein like characters of reference designate corresponding parts throughout the several views, 1, indi-

cates the base or frame of a suitable crozing, chamfering or hollowing machine or any type of machine for operating on a temporarily assembled barrel, and wherein the barrel is rotated during such operation.

5 In the embodiment of the machine illustrated, suitable cylindrical standards 2 slide longitudinally of the base or frame 1 are employed, the same being moved by 10 suitable lever mechanism 3 to engage the opposite ends of a temporarily assembled barrel 4 adapted to be rolled between the same. The members 2, carry on their interior, suitable mechanism 5, for engaging 15 the ends of a barrel and rotating the same on the operation of the lever 3, to force the members 2 into contact with the opposite ends of the barrel.

In the preferred embodiment of the machine illustrated, a member 6, for crozing the 20 end of the barrel is carried on each of the members 2, the same being supported by a shaft 7 and driven by a belt 8. Coöoperating with each of the crozing members 6, is a suction duct 9, for withdrawing the severed 25 material from the interior of the barrel. As both of the crozing mechanisms for acting on opposite ends of the barrel are identical, it is only thought necessary to illustrate 30 one.

Supported by brackets 10, one extending upwardly from one of the members 2 and the other extending upwardly from the sliding base 11 supporting said member 2 is a 35 supporting shaft 12 fulcrumed at its opposite ends in bearings 13 and carrying intermediate of its length a suitable arm 14 through an opening in the outer end of which extends an adjustable link 15 connected at its lower end by a crank 16 with the lever 3 for operating the member 2 associated therewith. A spring 17 positioned intermediate the upper surface of the outer end of the arm 14 and a plate 17' carried by 40 the upper end of the link 15 provides a yielding connection between the link and arm, as in Fig. 1 of the drawings. On the outer end of the supporting shaft 12 is carried a suitable U-frame 18, in which is rotatably mounted a suitable marking or printing roller or wheel 19 supported by a shaft 20 projecting at its opposite sides from the hub 21 thereof, the opposite ends of said shaft being movable longitudinally through 45 bearings 22 in the outer ends of the side walls of the U-frame 18. The marking or printing roller or wheel carries on its peripheral surface suitable marking means or characters 23, preferably arranged in some 50 fixed manner, if numbers or letters are employed, the same are preferably arranged in a consecutive manner. An inking roller or other supply 23 rotatably mounted in a frame 55 pivoted as at 26 to the rear of the U- 60 frame 18 is normally maintained in fric-

tional contact with the periphery of the printing wheel 19 by the spring 27 and this supplies ink or marking material to the marking means 23 on each revolution of the roller or wheel 19.

To prevent the characters 23 on the roller or wheel 19 from overlapping as printed on the barrel on successive revolutions thereof, it is preferable that the characters be 70 printed on the barrel in a spiral circumferentially thereof and to accomplish this result, the printing wheel 19 is normally maintained in the position as in Fig. 3 of the drawings by a spring 28, the free end of which contacts with one face of the hub 21, said spring being supported by the U-frame 18. A spiral guide 29 is carried by the U-frame 18 at the opposite side of the hub 21 from the spring 28, and with said guide cooperates a guide finger 30, carried by the 75 hub 21. It will thus be apparent that during each complete revolution of the wheel 19, the finger 30, in its travel on the guide track 29, will cause longitudinal movement of the shaft 20 in the bearings 22, and thus cause a spiral printing of the characters on the barrel staves. The inking roller 24 is of such width that the printing roller is in contact therewith during the full longitudinal movement of the shaft 20 and the bearings 80 90 95 22.

The operation of the levers 3 to move the guide member 2 into contact with opposite ends of the assembled barrel 4 in the crozing of the ends thereof, causes one of the levers 3 to depress the arm 14, which forces the characters 23 of the wheel 19 into contact with the outer surface of the barrel adjacent one end thereof, consequently on the rotation of the barrel in the crozing thereof, the characters 23 will be printed on the outside of the staves thereof, and as the crozing is performed in a single revolution only a single revolution of the printing wheel 19 is required. In order to prevent the characters printing on the barrel from overlapping, the wheel in its rotation is moved a slight distance longitudinally of the barrel due to the movement of the finger 30 on the spiral guide 29. On the return of the hand levers 3 to their normal position the weight of the rear end of the U-frame 18 raises the roller 19 from in frictional contact with the barrel; it will thus be apparent that an apparatus has been provided whereby the position of the staves of a temporarily assembled barrel relative to each other may be readily indicated during one of the necessary operations on the barrel, so that when the barrel is knocked down and it is desired to re-assemble the same, the position of the staves may be readily ascertained and the barrel as originally temporarily constructed may be again assembled.

Having thus described our invention what 130

is claimed as new and desired to be protected by Letters Patent is:

1. A barrel stave marking apparatus comprising means for rotating a barrel, a member provided with marking characters and adapted to be forced into frictional contact with the outer surface of the staves of a temporarily assembled barrel, means for supplying a marking medium to said marking characters for causing an imprint thereof on the barrel staves, said member capable of movement to place said characters in a spiral circumferentially of the barrel on the rotating of the same. 5
- 10 2. A barrel stave marking apparatus comprising means for rotating a barrel, a printing member provided with a plurality of marking characters normally disengaged from the barrel, an inking member coöperating with said printing member for supplying a printing medium thereto, a pivotally mounted frame supporting said inking and printing members and normally maintaining said printing member disengaged from the barrel whereby 15 said barrel is capable of movement independently of said printing member, and manually operated means for pivoting said frame to force said printing member into contact with the barrel to cause an imprint of the 20 characters thereon circumferentially of the barrel during the rotation thereof. 25
- 25 3. A barrel stave marking apparatus comprising means for rotating a barrel, a wheel provided on its surface with marking characters and mounted to operate on an axis parallel with the axis of rotation of the barrel, said wheel normally lying in disengagement from the barrel thereby permitting independent rotation of the barrel, 30 manually operated means for yieldably forcing the periphery of said wheel into frictional contact with the barrel whereby said 35 wheel and barrel rotate in unison, and means for supplying a marking medium to said characters whereby the same are imprinted circumferentially of the barrel during the 40 contact of said wheel therewith during the rotation of said barrel. 45
4. A barrel stave marking apparatus comprising means for rotating a barrel, a wheel provided on its periphery with marking characters and mounted to rotate on an axis parallel to the axis of rotation of the barrel, 50
- means for moving the wheel longitudinally of the barrel during each complete revolution thereof, means for restoring the same to normal position on each complete revolution thereof, and means for supplying a marking medium to said characters and over which the said wheel moves. 55
5. A barrel stave marking apparatus comprising means for rotating a barrel, a member normally lying in disengaged relation from the surface of the barrel and rotatable on an axis parallel with the axis of rotation 60 of the barrel, said member provided with marking characters, means for forcing said member into frictional contact with the surface of the staves of the rotating barrel to cause said member to move with said barrel 65 whereby an imprint of said characters is placed circumferentially of the barrel, and means for moving said member longitudinally of the barrel during its rotation. 70
6. A barrel stave marking apparatus comprising means for rotating a barrel, an eccentrically pivoted frame positioned adjacent the barrel, a shaft supporting said frame, a marking roller rotatably mounted in one end of said frame on an axis parallel 75 with the axis of rotation of the barrel and provided with marking characters on its peripheral edge, an inking roller rotatably mounted in the other end of said frame to overbalance the weight of the marking roller 80 to maintain the same normally raised from contact with the positioned barrel, means for maintaining said inking roller in frictional contact with the marking characters of said marking roller, an arm extended 85 from said shaft, a lever, and a yieldable connection between said lever and arm for forcing said marking roller into contact with the barrel on the operation of said lever. 90
